FLOAT VALVE

Frederic L. Tarleton, Greenville, Mich., assignor
to Gibson Electric Refrigerator Corporation,
Greenville, Mich., a corporation of Michigan

Application May 20, 1933, Serial No. 671,983

2 Claims. (Cl. 137—103)

This invention relates to float valve constructions, and particularly to float valves for refrigeration and other uses where fluid is to be retained under pressure in a receptacle until a certain level is attained, and then to be allowed to escape through the valve controlled by the float, the effect of such control being to maintain the liquid level substantially constant.

An important object of the invention is the provision of a float valve so designed that the valve seat is wiped by the obturating element at every valve actuation in a manner calculated to keep the seat clean and thereby insure full closing and tight sealing of the valve without the 15 possibility of interference by dirt particles or other foreign matter.

Another object is the provision of a valve possessing these important and advantageous characteristics which is nevertheless of very simple 20 and inexpensive construction.

Other objects and advantages will be apparent from the following description, wherein reference is made to the accompanying drawing illustrating a preferred embodiment of my invention 25 and wherein similar reference numerals designate similar parts throughout the several views.

In the drawing:

Figure 1 is a transverse section of a tank incorporated in the "high" side of a refrigerating system, within which a constant minimum liquid level is desired to be maintained, and the contents of which may be at higher pressures than succeeding portions of the system, showing installed therein a float valve incorporating the principles of this invention, the liquid level being shown at the predetermined minimum and the valve closed;

Figure 2 is a similar view showing the liquid above the predetermined level and the valve 40 open;

Figure 3 is an enlarged side elevation view of the valve mechanism, fragmentarily showing the tank and float;

Figure 4 is a section taken substantially on 45 the line 4—4 of Figure 3 and looking in the direction of the arrows, and

Figure 5 is a perspective view of the combined float arm and actuating lever.

Referring now to the drawing, reference character 10 designates a tank, such as a receiver incorporated in the "high" or pressure side of a refrigerating system, although as will be apparent, my improved valve construction is equally usable in other applications. The tank 10 has 55 an inlet 10a opening into its top portion and an

outlet tube 12 running from a point nearer the bottom of the tank to an evaporator (not shown) or other subsequent portion of the system.

Serving as an outlet coupling for the tube 12 and projecting into the tank, in whose side it is sealed, is a float supporting and valve block 14 having an interior bore 16 communicating with the outlet tube and a valve orifice 15 forming the terminus of a lateral continuation of the bore 16 and opening in a smoothly finished side surface of the block. The valve orifice may sharply overhang the interior bore, as best shown in Figure 4, to eliminate all areas near the valve seat where accumulation of foreign matter might be undesirable.

The float 18 is shown as of hollow sheet metal construction and pivotally supported from the block 14 by a lever arm 20 formed as an inverted U-shaped sheet metal stamping pivoted on a pin 22 carried by the block 14 and having flanges as 75 19 at its float end by means of which it is attached to the float, as by means of spot welding. Float lever 20 also constitutes a bellcrank by virtue of the downwardly extending arm 21 which projects therefrom along one side of the block 14. 80 As best shown in Figure 4, the arm 21 is spaced from the block 14 and projects downwardly on the side of the block in which the valve orifice opens to a point beyond that orifice.

In the lever arm 21, in alignment with the orifice in one position to which the downwardly extending arm may be moved, is an aperture as 85 24 in which is retained an obturating or valve member 25 having a stem portion loosely projecting through but retained by the aperture 24, and 90 a head portion larger than the aperture and bearing against the side of the block, the head being adapted to close the valve orifice when the arm 21 is moved, as by means of the float, to a predetermined position in which the valve head 95 covers the orifice. The valve head is urged against the side of the block by means of a leaf spring 26 secured to the float arm 20 as at 28 and bearing against the end of the valve stem, as best shown in Figure 4. If the spring is supported by a single screw, as shown, angular displacement of the spring may be guarded against by projection of the pin 22 beyond the bracket 20 beside the spring, and by integrally turning out a lug as 23 from the arm 21 on the other side of the spring. The member 20 will be seen to constitute a bellcrank actuatable by the float as it rises and falls to move the valve member 25 to and from a position to which it blocks the valve orifice 15. It will also be seen that pres- 110

sure within the tank 10 assists the spring 26 in holding the valve against its seat, and that due to its wiping action the valve cannot be prevented from seating properly by grit or foreign matter.

5 While it will be apparent that the illustrated embodiment of my invention herein disclosed is well calculated to adequately fulfill the objects and advantages primarily stated, it is to be understood that the invention is susceptible to 10 variation, modification and change within the spirit and scope of the subjoined claims.

What I claim is:

1. In a float valve construction, a supporting member having a valve orifice opening in one face 15 thereof, a float, means including an arm pivotally connecting the float to the support, another relatively thin and flat arm connected to the first and movable in response to movement thereof 20 across and substantially parallel to the orificed face of the supporting member, a valve member supported by said last mentioned arm and having a head portion between the arm and support and engaging the latter, and a reduced stem portion 25 slidably projecting through and from the arm, whereby the valve is movable across the orificed surface of the support to and from a position in which it blocks the orifice, a leaf spring carried by said second mentioned arm and bearing 30 against the stem portion of the valve to urge the

head portion toward the orificed surface of the support, and a pivot pin pivotally securing both said arms to the support and projecting beside the spring to prevent undesired lateral movement thereof.

2. In a float valve construction, a combined supporting and outlet block having a valve orifice opening in one face thereof, a float appurtenant the block, an arm for connecting the float and block comprising a sheet metal element straddling and pivoted to the block and having a flattened portion movable relatively to the block across the orificed face thereof, a valve member having a head portion larger than the orifice arranged between the arm and block and having a reduced stem portion projecting through and from the other side of said arm and adapted to be moved wipingly over and from said orifice upon swinging of the arm through a possible path of movement, pivot pin securing the arm to the block and projecting from the arm on the same side as the valve stem, another projecting portion carried by the arm on the same side thereof, and means urging the valve member against the orificed face of the block, comprising a leaf spring carried by the arm and arranged between said last mentioned projecting portion and the projecting end of the pin.
